TEXTILE SPINDLE BRAKE DEVICE

Allen Raymond Andrews, West Hartford, Conn., assignor to Standard Screw Company, a corporation of New Jersey

Application November 1, 1956, Serial No. 619,725

5 Claims. (Cl. 57—88)

This invention relates generally to textile spinning or twisting apparatus and more particularly to an improved form of brake device for braking application to a spindle in apparatus of this sort.

Briefly described, the improved spindle brake device of the present invention is characterized by a brake lever arranged to rest in fulcrumed relation at the spindle base so as to carry a friction shoe adjacent one end thereof for braking application at a rotational surface of the spindle, the brake lever having a handle portion at its other end on which a leaf spring is mounted to extend in abutment with the spindle base in a manner serving to bias the brake lever to a normal position maintaining the friction shoe thereon inactive, and further serving to retain the fulcrummed brake lever resting on the spindle base, while at the same time allowing it to be rocked for braking application of the friction shoe, and also permitting removal of the brake lever readily from the spindle base simply by lifting it therefrom whenever desired.

These and other features of the present invention are described in further detail below in connection with the accompanying drawings, in which:

Fig. 1 is a vertical section detail showing a brake device embodying the present invention arranged on a textile spindle;

Fig. 2 is a side elevation of the brake device and spindle as seen from the right in Fig. 1; and

Fig. 3 is a vertical section detail corresponding generally to Fig. 1 but showing a modified arrangement of the brake device.

In Figs. 1 and 2, the spindle brake embodiment of the present invention shown therein is indicated generally by the reference numeral 10 and the spindle on which it is arranged by the reference numeral 12. The spindle 12 comprises a spindle blade 14 fitted from its upper end with a filler sleeve section 16 for receiving a bobbin or other yarn carrier thereon. A whorl 18 is also fixed to the spindle blade 14 above a fixed base 20 in which the spindle blade 14 is rotatably carried. The illustrated spindle base 20 is of the form disclosed in copending applications Serial No. 447,977, filed August 5, 1954, now Patent No. 2,781,629, and Serial No. 493,274, filed March 9, 1955, now Patent No. 2,781,628, in which complementary housing halves are assembled lengthwise about the lower spindle blade portion to form a composite base therefor, reference being made to the above noted copending applications for further details of this spindle base arrangement which forms no part of the present invention. The exterior surface of the spindle base 20 is threaded to engage a clamping collar 22 by which the spindle 10 may be secured on a spindle rail 24 in the usual manner.

The spindle base 20 is further arranged according to the present invention with bracket means 26 at the portion thereof overlying the spindle rail 24 and disposed just below the spindle whorl 18. The bracket means 26 arranged on the spindle base 20 preferably comprises a

2

pair of spaced bracket arms which extend upwardly above the lower end of the whorl 18 and are spaced outwardly thereof with vertical slots 28 opening upwardly at the upper bracket arm ends. In addition, a downwardly facing horizontal shoulder 30 is formed on the spindle base 20 adjacent the lower end of the bracket means 26. When the spindle base 20 has a composite form as disclosed in the above noted copending applications, one of the pair of bracket arms forming the bracket means 26

5 may be formed on each of the complementary halves forming the spindle base 20, and the horizontal shoulder 30 may likewise have components thereof formed on each complementary spindle base half so as to extend between the lower ends of the bracket arms forming the bracket means 26 when the spindle base 20 is assembled.

The spindle brake 10 provided according to the present invention comprises a brake lever 32 fitted with a fulcrum pin 34 by which it is arranged to rest in the vertical slots 28 in fulcrumed relation at the upper end of the bracket means 26. One end of this fulcrumed brake lever 32 is formed to carry a friction shoe 36 disposed for braking application at a rotational surface of the spindle 12, such as a flange 18' at the lower end of

20 whorl 18. The other end of the brake lever 32 is formed as a handle portion 38 depending from the bracket means 26 with a leaf spring 40 mounted thereon to extend upwardly and inwardly in abutment with the side of the spindle base 20 below the horizontal shoulder 30 thereon.

The leaf spring 40 is arranged in this manner so that it biases the brake lever 32 to a normal position at which the handle portion 38 thereof is rocked outwardly to cause the friction shoe 36 to bear laterally at a top surface of the spindle base 20 in inactive relation with respect to the whorl flange 18', but disposed for braking application thereto upon inward rocking of the handle portion 38. By this arrangement, the spindle brake 10 is normally retained on the spindle base 20 in an inactive position at which it is always ready for convenient braking application to the spindle 12 whenever needed, and at which it is always readily removable from the spindle 12, whenever desired, simply by manual retraction of the leaf spring 40 toward the handle portion 38

25 sufficiently to clear the horizontal spindle base shoulder 30, whereupon the spindle brake 10 may be simply lifted from the vertical slots 28 in the spindle base bracket means 26. It will also be noted that the spindle brake 10 may be just as readily replaced on the spindle base 20.

The modified embodiment of the present invention shown in Fig. 3 of the drawings comprises a spindle brake indicated generally by the reference numeral 50 arranged on a textile spindle 52 comprising a spindle blade 54 and a whorl 56 fixed thereon above a spindle base 58, which

30 in this case is illustrated as being of conventional tubular form; the spindle base 58 being externally threaded to carry a clamping collar 60 for securing on a spindle rail (not shown) as noted in connection with the previously described embodiment.

In the presently described embodiment, the spindle base 58 is likewise formed with bracket means 62 which may comprise spaced bracket arms having upwardly opening vertical slots 64 at the upper ends thereof and a downwardly facing horizontal shoulder 66 extending between the lower ends thereof on the base 58. The spindle brake 50 again comprises a brake lever 68 fitted with a fulcrum pin 70 at which it rests in fulcrumed relation in the vertical slot 64 on the bracket means 62 with one end thereof carrying a friction shoe 72 disposed for braking application at a lower end whorl flange 56'. Also, the other end of the brake lever 68 is again arranged to form a handle portion 74 depending from the

bracket means 62 with a leaf spring 76 mounted thereon to extend upwardly and inwardly in abutment with the spindle base 58 below the horizontal shoulder 66.

In this case, however, the leaf spring 76 is arranged to bias the brake lever 68 normally to a more or less balanced hanging position at which the friction shoe 72 rides inactively at or adjacent the whorl flange 56', so as to be applied thereto immediately for braking the spindle 50 upon application of inward rocking pressure at the handle portion 74 of brake lever 68 and thereby provide a more rapid braking reaction than is possible with the spindle brake arrangement of the first described embodiment. Also, it should be noted that in the presently described embodiment the balanced hanging disposition of the brake lever 68 allows the leaf spring 76 to be arranged with its extending end seated against the spindle base 58 directly at the downward face of the horizontal shoulder 66 to provide for retaining the spindle brake 50 on the spindle base 58 with somewhat greater stability, while allowing it to be removed and replaced thereon just as readily as the previously described embodiment.

The present invention has been described in detail above for purposes of illustration only and is not intended to be limited by this description or otherwise except as defined in the appended claims.

I claim:

1. A textile spindle brake device for braking application to a spindle at a rotational surface thereof adjacent a fixed base in which said spindle is rotatably carried, said device comprising fulcrum bracket means on said base, a horizontal shoulder on said base adjacent said bracket means, a brake lever removably resting in fulcrumed relation on said bracket means, a friction shoe carried at one end of said brake lever above said base for braking application at said rotational spindle surface, the other end of said brake lever forming a handle portion and depending from said bracket means with a leaf spring mounted thereon to extend upwardly and inwardly in abutment with said base below said shoulder, said leaf spring serving to bias said brake lever to a normal position maintaining said friction shoe inactive and further serving to retain said brake lever resting on said bracket means while allowing said brake lever to be rocked on said bracket means for braking application of said friction shoe and remaining retractable to clear said shoulder and thereby permit removal of said brake lever readily from said base simply by lifting it therefrom.

2. A textile spindle brake device for braking application at a whorl flange on a spindle blade rotatably carried in a fixed base, said device comprising a pair of spaced bracket arms on said base extending upwardly above the level of said whorl flange and spaced outwardly thereof, said bracket arms having vertical slots opening upwardly at the upper end portions thereof and having a horizontal shoulder extending on said base between the lower ends thereof, and a brake lever fulcrumed on said bracket arms at said upper end slots, said brake lever being fitted with

a friction shoe disposed for braking application to said whorl flange and having a handle portion depending from said bracket arms with a leaf spring mounted thereon and extending upwardly and inwardly therefrom to bear against said base below said horizontal shoulder, said leaf spring biasing said brake lever for normally maintaining the friction shoe thereon inactive and serving by abutment with said base below said shoulder to retain said brake lever on said bracket arms while allowing manipulation of said brake lever to apply said friction shoe at said whorl flange and remaining retractable to clear said shoulder and thereby permit removal of said brake lever readily from said base simply by lifting it therefrom.

15 3. A textile spindle brake device comprising, in combination with a spindle blade, a fixed base rotatably carrying said spindle blade, and a whorl secured on said spindle blade and formed with an exterior flange disposed adjacent said base, a pair of spaced bracket arms on said base, a downwardly facing horizontal shoulder on said base adjacent said bracket arms, a brake lever removably resting on said bracket arms in fulcrumed relation, a friction shoe carried at one end of said brake lever above said base for braking application at said whorl flange, the other end of said brake lever forming a handle portion and depending from said bracket means with a leaf spring mounted thereon to extend upwardly and inwardly in abutment with said base below said shoulder, said leaf spring serving to bias said brake lever to a normal position maintaining said friction shoe inactive and further serving to retain said brake lever resting on said bracket means while allowing said brake lever to be rocked on said bracket means for braking application of said friction shoe and remaining retractable to clear said shoulder and thereby permit removal of said brake lever readily from said base simply by lifting it therefrom.

20 4. A textile spindle brake device as defined in claim 3 and further characterized in that said leaf spring is arranged to bias said brake lever to a normal position at which the handle portion thereof is rocked outwardly to cause said friction shoe to bear laterally at a top surface of said base in inactive relation with respect to said whorl flange but disposed for braking application thereto upon inward rocking of said handle portion.

25 5. A textile spindle brake device as defined in claim 3 and further characterized in that said leaf spring is arranged to bias said brake lever to a normal position at which the friction shoe thereon rides inactively at said whorl flange but may be applied thereto for braking said spindle by inward rocking of said handle portion.
